United States Patent Office

Des. 179,773
Patented Feb. 26, 1957

179,773

RING BOX

Erwin Kalla, Pittsburgh, Pa., assignor to Barnett Davis,
Inc., Pittsburgh, Pa., a corporation of Pennsylvania

Application August 7, 1956, Serial No. 42,533

Term of patent 14 years

(Cl. D86—9)

Fig. 1 is a top plan view of a ring box embodying my design;
Fig. 2 is a bottom plan view thereof;
Fig. 3 is a face view of Fig. 1;
Fig. 4 is an end view of Fig. 1;
Fig. 5 is a rear view of Fig. 1; and
Fig. 6 is a perspective view of Fig. 1, with the lid of the box raised.

I claim:
The ornamental design for a ring box, as shown.
